APPARATUS FOR BENDING RODS OF
CORUNDUM AND SPINEL

Donald M. Yenni, Kenmore, N. Y., assignor to
The Linde Air Products Company, a corpora-
tion of Ohio

Application July 25, 1946, Serial No. 636,060

9 Claims. (Cl. 49—7)

1

This invention relates to an apparatus for bending a rod of corundum or spinel to form a bend of the desired angular extent and has for an object to provide a simplification in the apparatus for accomplishing this result. A further object is to provide a machine capable of bending such rods with minimum breakage. Another object is to provide such an apparatus which is adapted to provide the desired results uniformly, quickly and easily, and almost automatically with little skill required of the operator. Yet a further object is to provide means for controlling the pitch of rod convolutions.

In the prior application of McCandless et al., U. S. Patent 2,485,979, issued October 25, 1949, are disclosed the broad principles required for bending rods of such materials.

The present invention is an improvement upon such prior invention and provides a simple apparatus for applying those principles to the bending of corundum or spinel rods.

Referring to the drawings:

Fig. 1 is a perspective of one embodiment of an apparatus according to this invention;

Fig. 2 is a section on the line 2—2 of Fig. 1;

Fig. 3 is a top plan view of a portion of the apparatus of Fig. 1;

Fig. 4 shows the rod in position before being bent;

Fig. 5 is the approximate shape of the rod at the conclusion of a 90° bending movement;

Fig. 6 shows the bending of the rod after a 180° movement;

Fig. 7 shows the completion of a 270° angular displacement, while

Fig. 8 shows the rod after it has been bent through 360°.

Referring to the drawings a substantially straight rod 10 of unicrystalline corundum or spinel is gripped in a chuck 11 supporting one end portion of the rod so that an intermediate part is exposed to a multi-flame burner 12 for heating such intermediate portion to a temperature at which the rod may be bent. The chuck 11 is easily removable being formed on the stem of the T shape shown in Figs. 1 and 3 as having the portion at a right angle to the stem received within an open slot in the end of the block 27 and secured in place by the two set screws illustrated. The selection of appropriate corundum rods for such bending is described in the aforementioned patent in that corundum rods having an optical orientation of 30° to 75° are preferred and still better those having such orientation of 40° to 50° are preferred. By optical orientation is meant

2

the angle between the optical axis and the longitudinal axis of the corundum rod. For selecting such rods with such orientation the angular relation of the optical axis with respect to the longitudinal axis of the rod is determined in ways familiar to those skilled in this art and some appropriate marking is made along one side of the rod to indicate the location of the plane common to the longitudinal and optical axes. With the common plane of both such axes generally horizontal the rod is clamped in the chuck 11 preparatory to its being heated to a temperature suitable for the desired bending. It has been pointed out in the aforementioned patent that the plane of bending should be between zero and 45° to the common plane and preferably coincident with the common plane through the optical and longitudinal axes, if breakage of the rods is to be reduced.

Each burner 12 may be for any convenient flame supplying sufficient heat from fuel such as natural gas, acetylene, hydrogen, propane, city gas etc. The particular arrangement of burner ports is not the only one suitable, but is a preferred arrangement found empirically to be satisfactory for maintaining a bending temperature above 1500° C. and below the melting point of the corundum or spinel rod being bent during the course of the bending operation.

Surrounding the burner 12 a radial arm 13 is secured by the set screw 14 to the rotatable pulley 15 and its shaft 16. The pulley 15 is mounted contiguous one side of the stationary bracket 31 opposite the arm 13. The arm 13 has a radial slot 17 cut therein along which the upstanding post 18 may be adjustably fastened by means of a nut 19 engaging threads on the post 18 and clamping the headed lower end on the post 20 against the bottom or underside of the slotted arm 13. A lock washer 21 assists in retaining the nut 19 in its adjusted position as is well known in the use of such washers. Rotatably surrounding the post 18 is a bifurcated arm 22 having a sleeve portion surrounding the post 18. The angularly extending dog 23 is clamped to the bifurcated arm 22 by the nut 24 on the underside of the arm engaging the stem 25 and holding the arm or dog 23 clamped in position. The arm 22 and post 18 are radially adjustable along the rotating arm 13 and dog 23 is adjustable along the arm 22. As shown in Fig. 2 for example, the end portion of the dog 23 which cooperates with the rod 10 is provided with a V-shaped notch 26 within which the rod 10 is adapted to be received. To lessen heat conduction from the rod 10 to the dog 23 and its supports, the sides 26 of the V notch

are preferably bevelled to form a knife edge on each side whereby contact with the rod is at two points where the knife edges engage the rod. This V notch assists in angularly moving the free end portion of the rod during the bending operation. The arms 13, 22, and 23 are adjustable to adapt the machine to different lengths of rods. Only one of these three arms is pivotally connected to the other and that is arm 22 which is pivotally mounted about the upstanding post 18 on the arm 13. By using the three arms illustrated it is possible to have the V notch over or nearly over the flame so that a comparatively short rod may be bent as desired.

The chuck 11 is seen to be slightly downwardly inclined as a result of the adjustment of the block 27 to which the chuck is shown as being fastened in Fig. 3. This block may be made adjustable to different degrees of inclination and may be adjusted in various ways such as by means of the pivots 28 supporting the block 27 and the bolt carrying adjustment nuts 29 and 30 below and above the block respectively which hold the block in the desired inclined position of adjustment. The horizontal arm 31 of a stationary bracket supports the burner 12 and rotatable arm 13 while a vertical portion 32 of the same bracket pivotally supports the block 27 adjacent an appropriate stationary wall as illustrated in Fig. 1.

As shown in Figs. 4 to 8 inclusive the burner block has a plurality of ports 33 through which issue fuel gas providing the numerous flames for heating the rod 10 both before and during the bending operation. The block 12 is supplied with fuel mixture through a suitable pipe 34 within the inner shaft 34a. For cooling the block against excessive rise in temperature, water or other cooling liquid is supplied through the pipe 35 to the block 12. After passing out of the burner block, the cooling liquid moves through the flexible pipes 36 and 38 to a cooling passage 37 within the horizontal arm 31 of the bracket. Cooling liquid then flows through pipe 39 out of said arm to either a drain or radiator for cooling the same. As shown in Fig. 1 the flexible connection 40 supplies fuel gas mixture from the mixing pipe 41 to the intake pipe 34 to the block 12.

As shown in Figs. 1 and 2 a belt 42 drives the pulley 15 from a smaller speed reduction pair of pulleys mounted on a vertical shaft 43 journaled in the stationary frame of the machine as illustrated. A second vertical shaft 44 drives the shaft through the speed reduction pulley and belt drive from a motor 46 through speed reducing mechanism 45. A rheostat 47 controls the speed of rotation of the movable arm 13 to a slow speed of about 10 R. P. M. or less. The snap switch 48 controls the circuit of the motor 46 enabling the drive motor and the rotating arm 13 to be stopped at any desired position in its travel so that the bend in the rod may be of any desired angular extent.

After clamping the unicrystalline rod 10 in the chuck with the plane of its optical and longitudinal axes substantially horizontal and inclined to the plane of the rotating arm 13 at a small acute angle as illustrated, the flames from the burner block are started and the intermediate portion of the rod over these flames is heated to between 1500° C. and the melting point at which temperature the rod is in condition for bending. At such temperature the motor is started and the arm 13 rotated or angularly dis-

placed in the counter clockwise direction illustrated in Figs. 4 to 8 inclusive. From these figures it will be apparent that the radius of curvature in the bent rod is determined by the length 5 of the heated portion and also by the angular extent of the bending movement imparted to the rod. It first is shown in Fig. 5 where the radius of curvature is large, but diminishes as the bending of the rod progresses. Due to the V notch 10 26 being moved in a substantially horizontal plane and due to the slight inclination of the rod 10 and chuck 11 as shown in Figs. 1 and 2, the cool outer end portion of the rod is free to pass under the clamped end of the rod and chuck without interference. The rod having a 360° bend shown in Fig. 8 is one type found proper for use as a thread guide in the textile machinery art while bends of greater or less extent may possess other uses.

Among the advantages of this invention may be mentioned the freedom from necessity of using a die or form in determining radius since the radius of curvature is dependent on the heated length and on the angular extent of the bending 25 movement. Changes in either affect the radius of bending. The speed of operation is slow enough to permit the apparatus to be stopped at any desired angular position of travel to control the extent of the bending movement. The 30 heating of the rod simultaneously when it is being bent insures uniformity in distribution of the heating and any flexural stresses set up in the material during such bending.

The product of the present method and apparatus may be highly flame polished if the rod has been heated hot enough to cause superficial melting, and is possessed of great hardness and smoothness adapting it for many uses. The adjustment in the height of the chuck 11 and in 35 its angle of inclination to the plane of rotation of the arm 13 may control the pitch or spacing of the convolutions formed in the bend. The crossed or overlapped portions of the bent rod are either contiguous one another, or separated. 40 The apparatus assists in providing uniformity in the bends.

The flame head consumes approximately 15 45 cubic feet per hour of oxygen and a smaller quantity of natural gas during pigtail formation. The bending cycle for rods up to $\frac{1}{8}$ inch in diameter requires about 30 seconds for preheating the rod and about 10 seconds for bending the rod. Rods of larger diameter will require more time for the bending operation and will need more heat and 50 a longer preheat period.

Bending of a corundum rod differs from the bending of an ordinary glass rod, for example, in numerous respects among which may be mentioned: (a) the need for having the plane of the 55 longitudinal and optical axes bearing a prescribed angular relation to the plane of bending. Glass may be bent in any direction with equal facility. (b) Corundum has a sharp melting point (that is, the viscosity-temperature curve shows a discontinuity of tremendous proportions) and therefore has a narrow useful plastic range. Glass on the other hand has a wide plastic range in the sense that its viscosity decreases along a fairly smooth curve as the temperature rises. (c) A mean temperature for bending corundum is higher than a mean temperature for glass bending. (d) Corundum and spinel are unicrystalline whereas glass and other amorphous materials are considered liquids under any temperature conditions according to many authorities.

I claim:

1. An apparatus for bending a rod of corundum or the like comprising stationary gripping means for an end of the rod, means for heating an intermediate portion of the rod to above a white heat, and means for engaging the end of the rod opposite said gripping means to bend the same, said last end engaging means including a rotatable arm, driving means for said arm, a post radially adjustable along said arm, a second arm pivotally secured to said post, and a dog adjustable along said second arm and provided with a V-shaped notch engaging said rod for angularly displacing one end of the rod with respect to the other about the heated portion, said V-shaped notch having the sides thereof sharpened as knife edges for point contacts with said rod to reduce heat transfer from the rod to the dog.

2. Apparatus for bending a rod of corundum or spinel comprising means for clamping one end portion of the rod and supporting the rod, a multi-flame block for heating an intermediate portion of the rod to a bending temperature, and a rotatable means having movement around said block for engaging the free end portion of the rod in bending it about its heated intermediate portion, the portion of said last mentioned means engaging the rod being shaped to reduce heat conduction from the rod, said last means including an arm pivotally secured to a rotatable carrier and dog projecting inwardly from said arm and clamped thereto, said dog engaging said rod at its inward end.

3. Apparatus for bending a rod of corundum or spinel comprising clamping means for supporting an end portion of the rod, a heater for a portion of the rod being bent, a tubular outer rotatable shaft surrounding an inner tubular shaft through which energy is supplied for said heater, and an arm projecting from said outer shaft for engagement with said rod at its end portion remote from said clamping means, said heater co-operating with a portion of the rod intermediate said arm and clamping means.

4. Apparatus for bending a rod of corundum or spinel comprising clamping means for supporting an end portion of the rod, a stationary heater for the portion of the rod being bent, a support for said heater, a shaft rotatable around said heater support, and an arm extending from said shaft and movable around said heater for bending said rod in its heated portion intermediate said clamping means and said arm.

5. Apparatus according to claim 4 in which said heater is of area to continue during the bending operation the heating of the portion of the rod being bent.

6. Apparatus for bending a rod of corundum or the like comprising stationary gripping means for an end of the rod, means for heating an intermediate portion of the rod to a bending temperature, and means for engaging the end portion of the rod opposite said gripping means to bend the same, said last end engaging means including a rotatable arm, driving means for said arm, a post projecting from said arm, a second arm pivotally secured to said post, a dog clamped to said second arm and engaging said rod for angularly displacing one end of the rod with respect to the other about said heated portion.

7. Apparatus for bending a rod of material like corundum or spinel having a sharp melting temperature and requiring heating during bending, said apparatus comprising in combination a burner block from which a plurality of flames is adapted to issue in the same general direction, a bending force applicator rotatable around said flames for at least 360° in bending a rod while the same is being heated, means for clamping an end portion of the rod to be bent with its longitudinal axis forming an acute angle with a plane of movement of said bending force applicator, means for supporting said bending force applicator adjacent said burner block, driving means for said bending force applicator, and fuel supply means for said flames leading to said burner block from a direction to be out of the path of movement of said bending force applicator and its driving means as well as said rod.

8. Apparatus for bending a rod of corundum or spinel comprising in combination a burner having a plurality of upwardly directed openings, means above and to one side of said burner for clamping an end portion of the rod to be bent with an opposite end portion of the rod free and an intermediate portion of the rod heated to its bending temperature by flames from said burner openings, a bending force applicator rotatable around said burner, fuel supply means to said burner, and a support for said bending force applicator below the upper end of said burner and through the axis of which said fuel supply means extends, said bending force applicator engaging the free end portion of the rod beyond said heated intermediate portion and being of a height to pass under the clamped end of said rod.

9. An apparatus for bending a rod of material having a sharp melting point and requiring heating of the rod during bending, said apparatus comprising clamping means for clamping one end portion of said rod leaving the other end portion free, and a burner having a plurality of openings for heating an intermediate portion of said rod, said burner being located on one side of said rod clamping means, fuel supply means leading to said burner and located to one side of and spaced from said rod clamping means, and a bending force applicator rotatably supported adjacent the free end portion of the rod, there being sufficient clearance around said applicator to enable the same to rotate through an angle of at least 360° while the rod is being heated and bent in a plane at a small acute angle to the clamped end of said rod and away from said fuel supply means, whereby said bending force applicator during its rotation will be free from any contact with either the clamped end of said rod or said fuel supply means.
